[57] CLAIM

The ornamental design for a apparatus for pressurized
cleaning of refrigeration circuits in automobile vehicle
engines, as shown.

DESCRIPTION

FIG. 1 is a perspective view of the apparatus for pressurized
cleaning of refrigeration circuits in automobile vehicle
engines of the invention;

FIG. 2 is a right side view thereof;

FIG. 3 is a rear view thereof;

FIG. 4 is a top view thereof;

FIG. 5 is a bottom view thereof;

FIG. 6 is a left side view thereof; and,

FIG. 7 is a front view thereof.
